United States Patent Office

Des. 227,768
Patented July 17, 1973

227,768

KEYBOARD TERMINAL OR THE LIKE

Luigi Di Benedetto, El Segundo, Calif., assignor to TRW
Data Systems, Inc., Torrance, Calif.

Filed July 13, 1971, Ser. No. 162,322

Term of patent 14 years

Int. Cl. D14—02

U.S. Cl. D26—5 C

Fig. 1

Fig. 2

Fig. 3

FIG. 1 is a perspective view of a keyboard terminal or the like embodying my new design, the right side presents a mirror image thereof and the bottom is plain;

FIG. 2 is a rear orthogonal view thereof; and

FIG. 3 is a perspective view of a second species thereof, the second species being substantially identical to the first species, with the exception of the numeric display window.

I claim:

The ornamental design for a keyboard terminal or the like, substantially as shown and described.
